UNITED STATES PATENT OFFICE.

HAROLD L. CRULL, OF TULSA, OKLAHOMA.

WIRE-LINE EQUALIZER.

Application filed March 19, 1928. Serial No. 262,946.

My invention relates to wire line couplings, and more particularly to devices of that character for connecting supporting cables to a counterweight, the principal objects of the invention being to distribute the weight equally to the several strands of the cable, and to adapt a coupling for spreading the strands to facilitate the equalization of the weight.

In accomplishing these and other objects of the invention I have provided improved details of structure, the preferred forms of which are illustrated in the accompanying drawings, wherein :

Fig. 1 is a perspective view of the coupling illustrating its application to a plurality of cables for supporting a counterweight.

Fig. 2 is a central longitudinal section through the device showing the relation of the cable and counterweight connectors.

Fig. 3 is a section on the line 3—3, Fig. 2.

Fig. 4 is an enlarged detail perspective view of the coupling.

Referring in detail to the drawings:

1 designates a fragmentary portion of a support frame such as may be used in connection with oil well pumping equipment for supporting a counterbalance mechanism including a sheave wheel 2 mounted adjacent the outer end of the support frame 1 and cables 3 which extend over and rearwardly from the sheave toward apparatus (not shown) whereby the apparatus, for example, pumping apparatus, may be counterbalanced in its operation. The illustration and description of the counterbalance mechanism are limited to those portions of conventional apparatus with which my invention is associated.

The downwardly extending portions of the cables are adapted to support a counterweight 4, and the cables and counterweight are connected by a special coupling member 5 embodying my invention.

The coupling member 5 is preferably of cast steel construction and comprises a rectangular-shaped body plate 6 having a laterally extending rounded boss 7 centrally positioned on one of the end edges thereof,

and an elongated opening 8 centrally located in the plate extending from the boss to a point adjacent the opposite end of the plate. The opening is provided chiefly for reducing the weight of the member.

Spaced inwardly from the longitudinal edges of the body plate adjacent one end thereof and spaced by the opening 8, are upstanding guide ears 9, each reenforced by spaced webs 10 extending outwardly from the outer faces of the ears to the longitudinal edges of the body member. The plate is provided with opposite aligned slots 11, each slot registering with the spacing between the web members that reinforce each ear, the slots extending from the edges of the plate to the outer faces of the ears. Vertically elongated and doubly tapering openings 12 are provided in the ears, and the plate slots provide communication between the openings 12 and complementary guide means presently described.

Depending from the bottom surface of the body 6 and aligned centrally with the ears 9 is a transverse arcuate guide segment or boss 13 having a peripheral groove 14 providing a semi-circular seat 15, the ends of the groove aligning with the slots 11 and openings 12 so that a single strand of cable 3 threaded through the openings 12 of the ears 9 may extend through the slots 11 and lie in the groove 14, the tapering openings, slots and groove forming a continuous passage and the members having said passage elements providing a seat of gradual curvature for seating the cable in an endless connection with the coupling member.

Formed on the portion of the body plate opposite the ears 9 are upstanding cable-receiving hook members 16 having side and end reinforcing ribs 17 and 18, the down-turned arms 19 of the hooks being spaced from the end edge of the body plate and having heads 20 positioned adjacent the body plate. The heads 20 are provided with openings 21 aligning with threaded openings 22 in the end of the body plate, aligned openings being adapted to receive cap screws whereby cables received by the hooks may be securely retained thereon. Each

hook therefore receives a loop or bend of the cable, whereby two strands of the cable serve to support each hook portion of the device.

5 Depending from the bottom of the body plate adjacent the longitudinal edges thereof and in a position between the ears 9 and hooks 16 suitable for balancing the strains on the cables, are weight-supporting brackets 10 23 having trunnions 24 protruding outwardly from their lower ends for connection with the support arms 25 of the counterweight 4. The trunnions are positioned with relation to the ears 9 and hooks 16 to 15 equalize the weight applied to the several strands of cable extending from the hooks 16 with that applied to the single strand extending through the ears 9, and for this purpose the brackets, and particularly the 20 trunnions, are closer to the hooks than to the ears.

I prefer to taper each opening 11 in both directions, and particularly to provide downwardly and inwardly curved upper walls 26 25 and oppositely curved lower walls 27 merging with the arcuate seat 15 in the segment 13; and may similarly form the recesses of the hooks, to provide curved bearing surfaces for the bends of the cable.

30 In applying the device on a number of cables for supporting a counterweight 4, as shown in Fig. 1, the cables are looped over the hooks 16 so that a double strand extends over the sheave from each of the hooks. A 35 strand is threaded through the ears 9 and guide segment 13 beneath the body plate so that the two spaced single strands extending from the ears over the sheave are spaced inwardly from the strands connected to the 40 hooks, for spaced operation over the sheave wheel.

Since four strands connect with the hooks 16 at one end of the coupling as compared with two strands connecting with the ears 9 45 at the opposite end thereof, a two-to-one ratio is established at a center between the hooks and ears, and in overcoming this variance the trunnions are spaced away from the ears in a horizontal plane a distance double their spacing from the hooks, and thus a one-to-one balance is established 50 in the coupling.

What I claim and desire to secure by Letters Patent is:

55 1. A weight-supporting coupling comprising in combination with a cable adapted to be looped to form a plurality of strands, a body member having a strand-receiving seat at one end and spaced strand-receiving 60 hooks at the other end each adapted to engage one of the loops of the cable.

2. A weight-supporting coupling comprising a body member having strand-receiving seats at one end and strand-receiving hooks 65 at the other end, and a bracket element de-

pending from the body member having means for engaging a weight.

3. A weight-supporting coupling comprising a body member having strand-receiving seats at one end and parallel strand-receiving hooks at the other end, and a bracket element depending from the body member having weight-receiving trunnions.

4. A weight-supporting coupling comprising a body member having strand-receiving seats at one end and parallel strand-receiving hooks at the other end, and a bracket element depending from the body member having weight-receiving trunnions adjacent the vertical plane of the hooks.

5. In a weight-supporting coupling, a body plate having strand-receiving slots adjacent one end, a depending segment having a groove connected with said slots, and strand-receiving hooks on the other end.

6. In a weight-supporting coupling, a body plate having oppositely directed strand-receiving slots adjacent one end and a depending segment having a semi-circular strand seat connected with said slots, and strand-receiving hooks on the other end of the body plate.

7. In a weight-supporting coupling, a body plate having oppositely directed strand-receiving slots adjacent one end and a depending segment having a semi-circular groove connected with said slots, strand receiving hooks on the other end of the body plate, and a bracket depending from the plate having trunnions adjacent the vertical plane of the hooks.

8. In combination with the cables of a counterbalance device, a coupling having spaced upstanding ears adjacent one end provided with openings for threading a strand of cable therethrough, and spaced hooks adjacent the other end to receive bends of the cable.

9. In combination with the cables of a counterbalance device, a coupling having spaced upstanding ears adjacent one end provided with openings for threading a strand of cable therethrough, spaced hooks adjacent the other end to receive bends of the cable, and weight-engaging means positioned to equalize the weights on the strands and the members of the bends.

10. A weight-supporting coupling comprising a body member having aligned transverse slots adjacent one end and a depending boss provided with a peripheral groove connecting said slots, upstanding ears on the body member having taper transverse openings, paired webs spaced by said slots and providing guides for cables extending through the openings of the ears, and hook members on the opposite end of the body member.

11. A weight-supporting coupling comprising a body member having upstanding

ears on one end provided with transverse openings, and hook elements on the opposite end of the body member having downwardly extending hook members spaced from the 5 end of the body member.

12. A weight - supporting coupling comprising a body member having strand seats

adjacent one end, hook members on the opposite end, and web elements on the upper face of the body member reenforcing said 10 hooks.

In testimony whereof I affix my signature.

HAROLD L. CRULL.
